[57] CLAIM

The ornamental design of holster for golf bag, is shown and described.

DESCRIPTION

FIG. 1 is a front elevational view of a holster for golf bag, showing my new design;

FIG. 2 is a rear elevational view thereof;

FIG. 3 is a right side elevational view, the left side being a mirror image thereof; and,

FIG. 4 is another front elevational view.

The broken line showing of a golf bag in FIG. 4 is for illustrative purposes only and forms no part of the claimed design.

FIG. 1

FIG. 4
